UNITED STATES PATENT OFFICE.

RE A. P. WRIGHT, OF WASHINGTON, DISTRICT OF COLUMBIA, ASSIGNEE TO JOHN
FRANCIS HEMENWAY, OF NEW YORK, N. Y.

PRESSURE-ROLL RELEASE FOR CLOTHES-WRINGERS.

1,220,046.

Specification of Letters Patent. Patented Mar. 20, 1917.

Application filed October 26, 1916. Serial No. 127,897.

To all whom it may concern:

Be it known that I, REA P. WRIGHT, a citizen of the United States, residing at Washington, in the District of Columbia, have invented certain new and useful Improvements in Pressure-Roll Releases for Clothes-Wringers, of which the following is a specification, reference being had therein to the accompanying drawing.

This invention relates to certain new and useful improvements in a pressure roll release for a clothes wringer, the object being to provide a release in which a resilient retaining member is employed coöperating with non-rotatable sliding boxes mounted in the top bar of the wringer frame in such a manner that by bowing the resilient member, the same can be contracted in order to move the ends thereof out of engagement of the slidably mounted boxes so as to allow the boxes to move vertically with the pressure screws carried thereby in order to release the pressure on the pressure rolls.

Another object of my invention is to provide the threaded boxes with beveled portions adapted to engage the free ends of the resilient member when forced into position within the wringer frame so as to allow the boxes to be reset after they have been released.

Another and further object of the invention is to provide a clothes wringer with sliding boxes so constructed that they are prevented from rotating within the bearing sleeves and are provided with means for limiting the upward movement in order to prevent the boxes from jumping out of the frame when the pressure is released.

Other and further objects and advantages of the invention will be hereinafter set forth and the novel features thereof defined by the appended claims.

In the drawings.

Figure 1 is a side elevation partly in section of a clothes wringer showing the application of my improved construction of pressure roll release thereto; and

Fig. 2 is a perspective view of a threaded box and bearing detached.

Like numerals of reference refer to like parts in the several figures of the drawing.

In the drawing I have shown a wringer frame 1 of the ordinary construction having slotted side bars 2 carrying a rigid top bar

3 which is preferably secured within the slotted portions of the side bars by a transversely extending bolt or pin.

Mounted within the slotted side bars are superposed bearings carrying pressure roll shafts 4 and 5 having the usual rubber pressure rolls 6 and 7, and provided with meshing gears inclosed by gear casings as clearly shown.

The upper bearings are provided with spring supports 8 carrying coil pressure springs 9 upon which are mounted bearing plates 10 carried by a pressure bar 11, the above construction of wringer being of one style of wringer now in use, and I have shown this particular form of pressure means, but I do not wish to limit myself to any particular construction of pressure means for exerting the pressure on the pressure rolls.

A vertical bore is formed in each end of the top bar 3 into which is driven a slightly tapered bearing sleeve 12, said sleeve being inserted from the under side of the bar so that the same will be held within the bore of the top bar by a wedging action so as to prevent the sleeve from moving vertically within the top bar after it has been placed in position, it of course, being understood that the bore of the sleeve is cylindrical throughout its length, and that the outer surface is only slightly tapered. The sleeve is provided with oppositely disposed offset portions forming grooves 13 adapted to receive the oppositely disposed ribs 14 of an internally threaded cylindrical box 15 when said box is placed in position in the bearing sleeve so as to allow the box to slide easily within the bearing for the purpose hereinafter fully described.

The bearing sleeve 12 is provided with a notch 16 into which extends a lug 17 formed on the lower end of the box 15 so as to limit the upward movement of the box within the bearing sleeve when said box is released. The box 15 has a greater length than the bearing sleeve 12 and is provided with a notch 18 adapted to receive the adjacent end portion of a flat spring 19 which is slidably mounted in guideways 20 on the under side of the top bar 3, said spring having a central bowed portion 21 which is engaged by the head 22 formed on the lower end of the shank 23 of a push button 24 which is slid-

ably mounted within a vertical bore formed in the top bar 3.

From the foregoing above description it will be seen that the free ends of the spring 19 are normally held extended so as to fit within notches 18 of the sliding boxes carried by the top bar of the wringer frame in order to hold the boxes rigidly within the bearing sleeves so that the pressure screws 24 mounted within the boxes can be adjusted so as to exert the proper pressure on the pressure rolls through the medium of the pressure springs, bearing plates and pressure bar as the pressure screws are brought into engagement with the bearing plates as they are screwed through the boxes so as to force the plates downwardly in order to compress the springs. When the push button 24^a is forced downwardly the spring 19 is contracted so as to draw the free ends from out of the notches 18 of the boxes 15 which allows the boxes to move vertically a predetermined distance within the bearing sleeves 12 so as to instantaneously release the pressure on the pressure rolls.

In order to provide means for resetting the release after it has been operated, I form the threaded boxes 15 with beveled portions 25 at their lower ends, adapted to engage the free ends of the spring 19 when forced downwardly into the boxes so as to force the free ends of the spring inwardly in order to allow the spring to expand into the notches 18 so as to lock the boxes in position within the bearing sleeves in such a manner that the pressure screws can be rotated to adjust the pressure means.

From the foregoing description it will be seen that I have provided a clothes wringer 40 with a frame having pressure rolls and pressure means for said rolls in connection with the movably mounted non-rotating boxes carrying pressure screws for adjusting the pressure means which are held in predetermined position by the resilient member so that when the resilient member is contracted through the medium of the push button the boxes will be released in order to release the pressure means.

50 I claim:

1. A clothes wringer, comprising a frame having pressure rolls and pressure means for said rolls mounted therein, movably mounted boxes carried by the top bar of said frame carrying pressure screws for adjusting said pressure means, a resilient member carried by the top bar detachably engaging said boxes for holding said boxes in predetermined position within said top bar, and means for bowing said resilient member for moving the ends thereof out of engagement with said boxes for releasing said pressure means.

2. A clothes wringer, comprising a frame 65 having pressure rolls and pressure means

for said rolls mounted therein, boxes slidably mounted in said frame carrying pressure screws for adjusting said pressure means, a resilient member detachably engaging said boxes for holding said pressure means in predetermined position, and means for contracting said resilient member for releasing said pressure means.

3. A clothes wringer, comprising a frame having pressure rolls and pressure means 75 for said rolls mounted therein, a top bar fixed in said frame having bearing sleeves, boxes slidably mounted in said bearing sleeves having notches, pressure screws mounted in said boxes for adjusting said pressure means, a resilient member carried by said top bar having its free ends extended into said notches for holding said boxes in predetermined position within said top bar, and means for contracting said resilient member for releasing said boxes.

4. A clothes wringer, comprising a frame having pressure rolls and pressure means for said rolls mounted therein, a top bar fixed in said frame having bearing sleeves, internally threaded boxes slidably mounted in said sleeves having means for limiting the upward movement thereof, pressure screws mounted in said boxes for adjusting said pressure means, a resilient member carried by said top bar detachably engaging said boxes for holding said boxes in predetermined position, and means for contracting said resilient member for releasing said boxes.

5. A clothes wringer, comprising a frame having pressure rolls and pressure means for said rolls mounted therein, a top bar fixed in said frame having bearing sleeves provided with oppositely disposed grooves and a vertically disposed slot, internally threaded boxes having oppositely disposed ribs slidably mounted in said bearing sleeves, said boxes having lugs projecting within the slots thereof for limiting the upward movement of said boxes, pressure screws mounted in said boxes for adjusting said pressure means, a member carried by said top bar for holding said boxes in predetermined position within said bearings, and means co-operating with said member for moving the free ends of said member out of engagement with said boxes.

6. A clothes wringer, comprising a frame having pressure rolls and pressure means for said rolls mounted therein, internally threaded boxes slidably mounted in the top bar of said frame having notches and provided with bevel portions beneath said notches, pressure screws mounted in said boxes for adjusting said pressure means, a resilient member carried by the top bar having its free ends extended into said notches for holding said boxes in position therein, and a push button for contracting said resil-

ient member for moving the free ends thereof out of said notches for allowing said boxes to move vertically within the top bar.

7. A clothes wringer, comprising a frame, having pressure rolls and pressure means for said rolls mounted therein, boxes slidably mounted in the top bar of said frame having beveled lower ends and notches, a centrally bowed resilient member slidably mounted on the under side of the top bar of said frame having its free end extending in the path of travel of said boxes and adapted to extend within the notches thereof for holding said boxes in predetermined position within said frame, and a push button slidably mounted in the top bar of said frame engaging said resilient member for moving the ends thereof out of said notches for releasing said pressure means.
- 20 8. A clothes wringer, comprising a frame having pressure rolls and pressure means for said rolls mounted therein, bearing sleeves fixed in the top bar of said frame having vertical slots, internally threaded boxes slidably mounted in said bearing sleeves having lugs extending into the slots of said bearing sleeve, pressure screws carried by said boxes for adjusting said pressure means, a member slidably mounted on the top bar having its ends seated within the notches of said boxes, and means for depressing said member for moving the ends thereof out of engagement with said notches for allowing said boxes to move vertically within said top bar.
- 25 9. A clothes wringer, comprising a frame having pressure rolls and pressure means

for said rolls mounted therein, bearing sleeves fixed in the top bar of said frame having vertically disposed slots, non-rotating boxes slidably mounted in said bearing sleeves having beveled lower ends, pressure screws carried by said boxes for adjusting said pressure means, a spring slidably carried by the top bar of said frame having its ends arranged in the path of travel of said boxes and adapted to be engaged by the beveled ends thereof, said boxes having notches above said beveled portions to receive the free ends of said spring, and means for bowing said spring for moving the free ends thereof out of the notches of said boxes for allowing said boxes to move vertically within the bearings of the top bar.

10. A clothes wringer, comprising a frame having pressure rolls and pressure means for said rolls mounted therein, internally threaded boxes slidably mounted in the top bar of said frame having pressure screws for adjusting said pressure means, means for limiting the upward movement of said boxes within said top bar, a resilient member carried by the top bar of said frame having its free ends detachably engaging said boxes for holding said boxes in predetermined position within said frame, and a push button slidably mounted in said top bar engaging said spring for moving the free ends of said spring out of engagement with said boxes for allowing said boxes to move vertically within said top bar.

In testimony whereof I hereunto affix my signature.

REA P. WRIGHT.
